CORNER REINFORCEMENT

Application filed May 5, 1930. Serial No. 449,830.

This invention is a reenforcement for a corner of a plastered surface, and has for its object to bind the plaster in the corner so as to prevent cracking, and also provide guide means for insuring a true right-angular corner having the apex of its angle extending in an exactly straight line.

More particularly it is an object of the invention to mount an elongated angle bead in the interior corner formed by the laths of a structure which is to be plastered, so that the bead forms a guide which will definitely determine the thickness of the plaster coating and insure a true right-angle surface with the apex of its angle forming a straight line.

It is a further particular object of the invention to provide an angle bead which will positively lock the plaster in an interior corner and thereby eliminate cracking.

Further objects of the invention will be readily understood from the following description of the accompanying drawing, in which:

25 Fig. 1 is a perspective view of the interior corner of a plastered wall, showing the improved reenforcement.

Fig. 2 is a transverse section on the line 2—2 of Fig. 1.

30 The invention is illustrated in connection with a usual interior corner of a frame structure adapted to receive a plaster coating and comprising right-angularly disposed cooperating studs 1 having laths 2 mounted thereon.

35 The reenforcement for the corner is an elongated angular bead adapted to be mounted on the laths at the interior corner which is formed thereby, and preferably comprising an elongated sheet metal strip. In cross-section the sheet metal strip is bent at right angles medially of its width so as to form wings 3—3, with the wings then bent so as to form acute angular ribs 4—4 projecting toward one another, and the outer edges of the

40 metal form marginal strips 5—5 in the planes of wings 3.

The right-angular bead is mounted on laths 2 in the corner of the framing, and extends the full length of the corner with suitable fastening means such as nails 6 driven

through the marginal strips 5 for securing the bead in place; and the wings 3 and ribs 4 are respectively provided with apertures 7 and 8 adapted to receive the plaster for locking it to the bead.

45 A plaster coating 9 is applied to laths 2 in the usual manner, and this plaster coating is also applied to marginal strips 5 and wings 3 of the bead, with the ribs 4 projecting into the plaster coating as shown in Fig. 2. 50 The plaster thus enters apertures 7 and 8 for locking it to the bead, and as shown in Fig. 2 the ribs 4 cooperate to form a dovetail groove for positively locking the corner portion of the plaster coating to the bead so 55 as to prevent cracking at the corner.

55 The plaster coating 9 is smoothed down to uniform and standard thickness by a usual darby A as shown in Fig. 2, and the ribs 4 project a distance whereby the darby by 60 resting at one end against the portion of the plaster coating which has already been reduced to standard thickness as shown at B, and resting at its opposite end against one of the ribs as shown at C, will gauge the plaster 65 coating to the desired standard thickness at one side of the corner, while end abutment of the darby against the other rib 4 as shown at D, will similarly reduce the plaster coating at the other side of the corner to the desired 70 standard thickness. The darby by its abutment C—D against the rib 4, thus forms a true right-angle surface for the corner of the plaster coating between the cooperating ribs, and said definite positioning of the darby 75 also insures the apex E of the angle which is formed by the corner of the plaster extending in a straight line as shown in Fig. 1.

When the plastering is completed at one side of the corner, the darby is of course similarly used upon the plaster surface at the other side of the corner, so that the face of the darby rests upon the rib 4 which projects from said other side of the corner, and its end surface abuts against the opposite rib 80 as previously described, thereby truing-up 85 said other side of the corner of the plaster.

When the plaster coating 9 is finished, the extreme apices of ribs 4 are of course visible through the surface of said coating as 100

shown at F, since the darby by its abutment against the ribs will have smoothed down the plaster coating flush with the apices of the ribs, but the usual finish coating of plaster which is then applied as shown at 10 will cover and conceal the apices of the ribs and thus provide a usual continuous surface when the plastering is completed. The finish coating 10 is relatively thin, and with the coating 9 forming a true right-angular corner with the apex of its angle in an exactly straight line, the thin coating 10 may be applied to this geometrically true foundation so as to readily maintain the desired exact angularity of the finished surface.

15 We have thus provided simple and inexpensive but practical means for reinforcing the corner of a plastered surface, so as to positively lock the plaster in the corner against the possibility of cracking and also readily gauge the plaster by a usual darby so as to insure uniform thickness at the corner, with said corner forming a true right-angle having its apex extending in an exactly straight line.

20 It will be noted that by forming the ribs 4 so that their sides form acute angles, the said ribs have wide bases providing a firm foundation whereby the ribs are rigid with relation to elements 3—5 of the bead, so that distortion of the ribs is avoided; and since the sides of the ribs project from elements 3—5 at angles greater than right angles, the chance of the plaster cracking at the junction of the ribs with the bead is appreciably less than if the ribs projected perpendicular- 25 ly therefrom. Furthermore by providing acute angular ribs rather than perpendicular ribs, the said ribs form vertical channels in back of the same which will be filled with plaster through apertures 8 so as to rigidly lock the ribs against distortion and provide a substantial plastic lock across the ribs between the plaster on the marginal strips 5 30 and the plaster in the angles which are formed by wings 3.

35 An extremely efficient and practical ribbed structure is thus provided, with the ribs securely held against distortion with relation 40 to the rest of the bead and reenforced by the plaster which forms locking keys extending across the back of the ribs, while at the same time positioning the ribs so that their apices are adapted for engagement by a usual darby 45 so as to form a guide for plastering the corner in which the bead is mounted.

We claim:

1. An angle bead adapted for embedding in a plastic material at a corner thereof and 50 having an abutment bent therefrom with the sides of said abutment convergently tapering to form a projecting acute angular apex, said apex of the abutment being adapted for engagement by a surfacing tool and said 55 abutment extending into the plastic material

from one side of the angle bead to a distance equal to the desired thickness of the plastic material, and said abutment having apertures opening through its respective sides in spaced relation from its apex, whereby the 70 plastic material is adapted to fill the apertures and the space in back of the convergently tapering abutment.

2. An angle bead adapted for embedding in a plastic material at a corner thereof and 75 having abutments bent from the respective sides of the angle bead with the sides of said abutments convergently tapering to form projecting acute angular apices adapted for 80 respective engagement by the face and end of a surfacing tool, and the abutments extending into the plastic material from the respective sides of the angle bead to a distance equal to the desired thickness of the plastic material, said abutments cooperating 85 to form a recess at the angle of said bead adapted to receive the plastic material for binding engagement, and said abutments having apertures opening through their respective sides in spaced relation from their 90 apices and adapted to receive the plastic material so that said plastic material fills the spaces in back of the convergently tapering abutments.

3. An angle bead adapted for embedding 95 in plastic material at a corner thereof and having abutments bent from the respective sides of the angle bead with the sides of said abutments convergently tapering to form 100 projecting acute angular apices adapted for respective engagement by the face and end of a surfacing tool, and the abutments extending into the plastic material from the respective sides of the angle bead to a distance equal to the desired thickness of the 105 plastic material, said abutments cooperating to form a dovetail recess at the angle of said bead adapted to receive the plastic material for binding engagement, and said abutments having apertures opening through their 110 respective sides in spaced relation from their apices and adapted to receive the plastic material so that it fills the spaces in back of the convergently tapering abutments and forms 115 an integral continuation of the plastic material in the dovetail recess.

In testimony whereof we have affixed our signatures.
